Inventor
Alfredo Domingo POU,

By Emile Sonnely et al.

Attorney

UNITED STATES PATENT OFFICE.

ALFREDO DOMINGO POU, OF BUENOS AIRES, ARGENTINA.

ELECTRIC LIQUID-HEATING SYSTEM.

Application filed October 20, 1923. Serial No. 669,782.

To all whom it may concern:

Be it known that I, ALFREDO DOMINGO POU, citizen of the Republic of Uruguay, residing at 186 Azcuena Street, Buenos Aires, Argentina, have invented certain new and useful Improvements in Electric Liquid-Heating Systems, of which the following is a specification.

My invention relates to a new system for heating all kinds of liquids by means of direct contact with electrodes, while also providing for a circulation of current centrally through the liquid, said system being applicable to boilers for generating steam, for heating all sorts of liquids and for effecting various chemical reactions, but more particularly to a boiler or auto-clave for water, in which alternating electric current is used as a heating means.

20 A clear idea of the disposition and form of the elements is given by the appended drawings, which show an apparatus according to my present invention specially devised for tri-phase current.

25 In the said drawings:

Figure 1, is a sectional view of one of the electrodes.

Figure 2, is a horizontal cross-section of the autoclave.

30 Figure 3, is a vertical central section of the same.

Similar characters of reference denote same or like parts throughout the said figures.

35 The electrode consists of a bar 1 on one end of which a small bar 2 is screwed, said bar 2 being in direct contact with the water within the boiler. For insulation purposes the bar 1 is enveloped in a cover of mica 3, and both elements are introduced into an externally screwthreaded tube 4 on which a stuffing box 5 is screwed against bar 2 so as to prevent the water in the boiler from entering said tube 4. Said tube 4 is firmly secured to the bar 1 by means of the piece 6. The outer end of bar 1 protruding from the said tube 4 has a portion 7 of square or like cross-section which allows the fixing thereon of a handle such as 16 in order to 45 rotate the electrode and to introduce it more or less within the boiler. Said bar 1 has also an outer screwthreaded portion 8 immediately beyond the square portion 7 on which, by means of the nuts 9, the terminals 55 of the electric cables are fixed.

The above electrode is introduced within an interiorly screwthreaded tube 10 having at its inner end a hinged cover 11 and closed at its outer end by a nut 12. The tube 10 is fixed to the body 13 of the boiler by a support 14 which carries a sliding door 15 in order to totally close the tube 10 when the electrode proper is in its outer position.

The electrodes may be placed on the circumferential wall of the boiler in two or more planes as shown in Fig. 3, or they may be placed at the top and bottom thereof. Their number in each plane may be three as shown, or there may be six connected two-by-two in parallel. 21, 22 and 23 are revolving blades which on rotating agitate the contents of the boiler so as to maintain a uniform temperature therein. The blades 21 are fixed to a central vertical shaft 24, the blades 22 are fixed to an intermediate 75 tubular shaft 25 and the blades 23 to the outer tubular shaft 26, the three shafts being nested, as shown. Said shafts may be rotated at any uniform or variable speed by suitable means such as the pulleys 27 fixed 80 on a horizontal shaft 28 which by means of a pinion 29 transmits movement to a pinion 30 on the shaft 24. Movement is transmitted to the intermediate shaft 25 from said shaft 28 by a toothed wheel 31 meshing with 85 a crown wheel 32, and to the outer shaft 26 by the intermeshing pinion and crown wheel 33 and 34.

The free ends of the tubular shafts 25 and 26 are provided with stuffing-boxes 35 and 36 to prevent the entrance of water therein.

It is obvious that many constructional and other changes may be introduced without departing from the scope of my invention, as hereinafter claimed.

Having now fully described and ascertained the nature of my present invention and in what manner the same is to be carried into practice, I declare that what I claim and desire to protect by Letters Patent is:—

1. An apparatus for electrically heating liquids, comprising a receptacle; a plurality of sets of electrodes projecting into the interior of the receptacle in different horizontal planes, with their inner ends in direct contact with the liquid to be heated, an agitator for the liquid disposed within said receptacle; and means for rotating the agitator.

2. An apparatus for electrically heating liquids, comprising a receptacle; a set of tubes projecting into the interior thereof; an endwise-adjustable electrode inserted through each tube and protruding beyond the same at its inner end, and a cover hinged to the inner end of each tube to close the same when the respective electrode is withdrawn. 5
3. An apparatus for electrically heating liquids, comprising a receptacle; a set of tubes projecting into the interior thereof; a support individual to each tube secured to said receptacle; an endwise-adjustable electrode inserted through each tube and protruding beyond the same at its inner end, and a door slidably carried by each support to close the respective tube when the electrode therein is withdrawn. 10
4. An apparatus for electrically heating liquids, comprising a receptacle; a set of tubes projecting into the interior thereof; a support individual to each tube secured to said receptacle; an endwise-adjustable electrode inserted through each tube and protruding beyond the same at its inner end; a door slidably carried by each support to close the respective tube intermediate its ends when the electrode therein is withdrawn; and a hinged cover on the inner end of each tube to close the same. 15
5. An apparatus for electrically heating liquids, comprising a receptacle; a set of supports secured thereto; an internally-threaded tube mounted in each support and projecting into the interior of the receptacle; an endwise-adjustable, externally-threaded tube mounted in the first-named tube and projecting beyond the inner end thereof; and an electrode in the second-named tube for adjustment therewith, the inner end of each electrode being in direct contact with the liquid to be heated. 20
6. An electric heater, according to claim 5, in which the inner end of each internally-threaded tube has a hinged cover to close the same when the associated externally-threaded tube and electrode are withdrawn. 25
7. An electric heater, according to claim 5, in which each support carries a sliding door to close the corresponding internally-threaded tube when the associated externally-threaded tube and electrode are withdrawn. 30
8. An electric heater, according to claim 5, in which each support carries a sliding door to close the corresponding internally-threaded tube intermediate the ends thereof when the associated externally-threaded tube and electrode are withdrawn, and in which the inner end of each said internally-threaded tube has a hinged closure. 35
9. An apparatus for electrically heating liquids, comprising a receptacle; a plurality of sets of electrodes mounted in the wall of the receptacle in different horizontal planes, with their inner ends in direct contact with the liquid to be heated; and means for causing a circulation of the liquid between the said inner ends of the electrodes. 40
- In testimony whereof I affix my signature. 45
